PIPE THREADER

Gilbert J. Sellmeyer, Indianapolis, Ind.

Application January 25, 1943, Serial No. 473,528

9 Claims. (Cl. 10—107)

This invention relates to pipe threading devices.

An object of this invention is to provide an improved power operated pipe threader which may be secured to the underside of a supporting stand or table.

Another object of this invention is to provide a pipe threading means including a pipe holding chuck, a reduction driving means and a motor connected with the driving means, the entire apparatus being positionable beneath a table such as a conventional pipe stand.

A further object of this invention is to provide in a device of this kind an improved guide means for supporting the pipe while it is being threaded so as to relieve the threading means of torsional strain or of whipping during the threading operation.

A further object of this invention is to provide in a device of this kind an improved driving gear assembly which is in the form of planetary gearing and is so constructed as to permit the ready changing of speed of rotation of the holding chuck.

A further object of this invention is to provide in a device of this kind an improved means for holding the chuck and chuck barrel in the selected gear speed.

To the foregoing objects and to others which may hereinafter appear, the invention consists of the novel construction, combination and arrangement of parts, as will be more specifically referred to and illustrated in the accompanying drawings, wherein is shown an embodiment of this invention, but it is to be understood that changes, variations and modifications may be resorted to which fall within the scope of the invention, as claimed.

Figure 1 is a detail top plan partly broken away of a pipe threading device constructed to an embodiment of this invention.

Figure 2 is a detail side elevation partly broken away of the device.

Figure 3 is horizontal section partly in detail through the device.

Figure 4 is a sectional view taken on line 4—4 of Figure 3.

Figure 5 is a sectional view taken on line 5—5 of Figure 3.

Figure 6 is a sectional view partly in front elevation of the device and taken on line 6—6 of Figure 2.

Figure 7 is a sectional view taken on line 7—7 of Figure 2.

Figure 8 is a sectional view taken on line 8—8 of Figure 3.

Referring to the drawings, the numeral 10 designates generally a stand which includes a table 11 having a plurality of supporting legs 12 secured thereto for supporting the table 11 at the desired elevation. In order to provide a means whereby a pipe may be threaded, I have provided a chuck 13 of conventional construction which is fixedly secured to a cylindrical tubular chuck barrel 14. The pipe is adapted to be extended through the barrel 14 and gripped or clamped by the chuck 13 with a portion of the base extending beyond the chuck 13 so that a pipe threading die structure 15 may be engaged with the projected portion of the pipe.

The die structure 15 includes an elongated handle 16 and in the present instance the handle 16 is adapted to contact against an elongated tubular stop member 17 during the threading operation. A second tubular stop member 18 is disposed at the opposite side of the table 11 from the tube 17 and the tube 18 is adapted to be engaged by the handle 16 during the reverse rotation of the chuck 13 or for cutting left hand threads.

The stop member 17 is slidably supported at one side of the table 11 by means of a pair of spaced apart bushings or sleeves 19 which are welded or otherwise fixed to the side of the table 11. The stop member 18 is also slidably relative to the table 11 being loosely mounted in supporting bushings or sleeves 20 which are welded or otherwise fixed to the table 11 opposite from the bushings 19. The stop members 17 and 18 are adapted to be shifted manually endwise so as to dispose a selected one of these stop members in an operative position in the path of the swinging movement of the handle 16.

The chuck barrel 14 is journaled in a housing generally designated by the numeral 21. The housing 21 is provided with a base 22 which in the present instance is uppermost and is secured by fastening bolts 23 to the lower side of the table 11. The housing 21 includes an annular wall 24 which has formed integral therewith an inwardly extending wall 25. A reduced diameter sleeve or bushing 26 is formed integral with the wall 25 and the sleeve 26 also has formed integral therewith a reduced diameter bearing sleeve 27. The sleeve 27 has mounted therein a plurality of antifriction bearing rollers 28 which engage the periphery of the chuck barrel 14 so as to rotatably support the barrel 14 in the bearing sleeve 27.

A sealing ring or washer 29 may be disposed in the outer end of the bearing sleeve 27 and may be positioned in an annular groove 30 formed in an inwardly projecting flange 31 carried by the bearing sleeve 27. The pipe which is extended through the barrel 14 may be held concentrically to the barrel by means of a removable bushing or sleeve 32 which is removably mounted in the rear end of the barrel 14. A flange 33 is formed integral with the sleeve 32 and limits the extension of the sleeve 32 in the barrel 14.

The chuck barrel 14 is rotated in the desired direction by means of a motor 34 which is preferably of the reversible type so that the barrel 14 may be rotated in the desired or selected direction. The motor 34 has an armature shaft 35 formed with a coupling flange 36. The coupling flange 36 is secured to a complementary coupling flange 37 which is carried by a shaft 38. The housing 21 includes a gear housing 39 which is offset to one side of the annular housing wall 24. The gear housing 39 includes opposed parallel walls 41 and 42 which are connected together by means of a connecting wall 43. The drive shaft 38 is journaled through the opposed walls 41 and 42, and has mounted thereon a gear 44 and the gear 44 meshes with a gear 45 which is fixed to a shaft 46, and a second gear 47 is smaller in diameter than the gear 45 and is also fixed on the shaft 46. The gear 47 meshes with a gear 48 which is mounted on a shaft 49 and a second gear 50 is fixed relative to the gear 48 and is of a diameter smaller than the gear 48. The gear 50 is in constant mesh with a large driving gear 51 which is mounted in the annular wall 24.

The gear 51 has formed integral therewith a cylindrical flange 52 and an annular flange 53 extends inwardly from the flange 52. A cylindrical bearing 54 extends from the annular flange 53 and is rotatable in the bearing or bushing 26. A plurality of antifriction rollers 55 are interposed between cylindrical member 54 and the inner side of the bearing 26. The cylindrical member 54 is provided at its outer end with an annular flange 56 which is formed with an annular groove 57. A set screw 58 is threaded through the bearing sleeve 26 and engages in the groove 57 so as to hold the sleeve 54 against endwise movement. The set screw 58 is locked in adjusted position by means of a lock nut 59.

The gear 51, which is termed a bell gear, has secured thereto a plurality of circumferentially spaced apart shafts 60 on which are mounted pinions 62. The pinions 62 mesh with an internally toothed ring gear 63 which is fixed by fastening members 64 to the inner side of the annular wall 24. The pinions 62 also mesh with a sun gear 65 which is keyed or otherwise fixedly secured to the chuck barrel 14. The two flanges 52 and 53 form an annular chamber 66 within which the gear 65 is adapted to be moved when the gear 65 is moved to a disengaged position with respect to the orbit gears 62.

The bell gear 51 also has secured thereto a second series of pinion shafts 67 on which are rotatably mounted planetary gears 68. The gears 68 are held in spaced relation to the adjacent side of the bell gear 51 by means of bearing sleeves 69 which may be cast with the bell gear 51 or may be in the form of spacing sleeves. The gears 68 (see Figure 5) also mesh with the fixed gear 63 and are adapted to be selectively meshed with a low speed sun gear 69 which is

keyed or otherwise fixed to the barrel 14 spaced from the gear 63. The housing 21 also includes a removable plate 70 which has formed integral therewith a cylindrical flange 71, an annular flange 72 and a bearing sleeve 73 which extends forwardly from the annular flange 72. The two flanges 71 and 72 form a gear chamber 74 within which the gear 69 is adapted to engage when the latter is in a disengaged position.

The gear 63 has formed integral therewith a sleeve 75 which is rotatable in the bearing sleeve 73 and the sleeve 75 is formed with an annular groove 76 within which rollers 77 are adapted to engage. The sleeve 75 is also formed with a pair of annular grooves or channels 78 and 79 on opposite sides of the groove 76 and a clutch pin 80 is adapted to engage in a selected one of the two grooves 78 and 79. The clutch pin 80 is slidable through an opening 81 formed in the bearing sleeve 73 and a clutch pin operating lever 82 is secured at an intermediate point along the length thereof by means of a pivot pin 83 to the outer end of the clutch pin 80. The clutch operating lever 82 is rockably mounted on a pivot member 84 carried by an ear or boss 85 which may be formed integral with the plate 70.

The clutch pin 80 is constantly maintained in a clutching position by means of a spring 86. One end of the spring 86 bears against a pin 87 extending diametrically through the pin 80, and the other or outer end of the spring 86 bears against a spring housing 88, which is secured about the spring 86 and in the present instance is secured by a fastening member 89 to the sleeve 73. The forward end of the sleeve 75 bears against a sealing washer 90 which is mounted in an annular groove 91 formed in the sleeve 73, and an annular flange 92 is formed integral with the sleeve 73 and provides a forward wall against which the sealing member 90 is adapted to bear. The plate 70 is adapted to be removably secured to the annular wall 24 by means of fastening members 93.

The pipe, during the rotation thereof, is rotatably supported in a guide structure generally designated as 94. The guide structure 94 includes an annular housing 95 which is formed at one end thereof with an integral annular flange 96 and a removable annular flange 97. Antifriction rollers 98 are mounted in the housing 94 and the rollers 98 may be of the type embodying the use of annular cages 99 at the opposite ends thereof. A removable bushing, including a cylindrical body 100 and an annular flange 101, is adapted to engage within the housing 94 and engage the rollers 98. The housing 94 is secured to a depending standard 102 formed with a base 103 which is secured by fastening members 104 to the lower side of the table 11 in a position spaced rearwardly from the collar or bushing 32. The motor 34 is provided with a base 105 which may be secured by fastening members 106 to the lower side of the table 11.

In the use and operation of this pipe threading mechanism, the pipe to be threaded is extended through the guide structure including the housing 94 and the bushing 100. The desired size bushing is inserted in the housing 94 so that there will be a minimum amount of play between the pipe and the bushing 100. A similar bushing 32 is inserted in the rear end of the chuck barrel 14, and the pipe then moved endwise through the chuck barrel 14 and the chuck 13. The pipe is then firmly clamped by the chuck 13. The motor 34 is then operated to rotate the chuck

barrel 14 in the desired direction. Where a fairly small diameter pipe is being threaded the gear 65, which is the high speed gear, is disposed in the position shown in Figure 3 where the gear 65 is in mesh with the planetary pinions 62. The reduction gearing, which includes the gears 44, 45, 47, 48 and 50, will rotate the bell gear 51. The gear 51 through the pinions 62 which are rotatably carried by the bell gear will rotate the driven gear 65.

If it is desired to rotate the chuck barrel and the chuck at a slower speed, as where a large diameter pipe is being threaded, the chuck barrel 14 is moved inwardly or endwise after first rocking the lever 82 outwardly so as to draw the clutch pin 80 out of the groove 78. The clutch barrel may then be moved inwardly, moving therewith the sleeve 75 and the gear 69 so that the gear 69 will be rotated by the planetary gears 68. At this time the clutch lever 82 is released so that the spring 86 will move the clutch pin inwardly into the low speed groove 79.

The die structure 15 is inserted on the projected end of the pipe and the handle 16 is engaged with, as an example, the stop member 17 which is manually moved forwardly in the path of the rotation or swinging movement of the handle 16. When the pipe has been threaded for the desired length the motor 34 may be reversed, thereby rotating the chuck 13 and the chuck barrel 14 in a reverse direction, at which time the handle 16 will swing over and engage the stop member 18.

A pipe threading mechanism as hereinbefore described will provide a power operated threading structure which may be secured to a portable pipe stand so that the pipe may be threaded either by means of the conventional hand operated die or it may be threaded by the power operated structure hereinbefore described.

What is claimed is:

1. In a pipe threading machine, work supporting and rotating means comprising a table and supporting legs, a housing dependingly secured to said table, a chuck barrel journaled through said housing, a chuck fixed to one end of said barrel, a pair of sun gears fixed on said barrel in spaced apart relation, a bell gear journaled about said barrel, a ring gear fixed in said housing, low speed pinions rotatably carried by said bell gear, high speed pinions rotatably carried by said bell gear, all of said pinions meshing with said ring gear, means for rotating said bell gear, and means carried by said housing holding a selected one of said sun gears in mesh with a selected group of said pinions.

2. In a pipe threading machine, work supporting and rotating means comprising a table and supporting legs, a housing dependingly secured to said table, a chuck barrel journaled through said housing, a chuck fixed to one end of said barrel, a pair of sun gears fixed on said barrel in spaced apart relation, a bell gear journaled about said barrel, a ring gear fixed in said housing, low speed pinions rotatably carried by said bell gear, high speed pinions rotatably carried by said bell gear, all of said pinions meshing with said ring gear, means for rotating said bell gear, a bearing sleeve fixed to one of said pair of gears and formed with a pair of annular clutch grooves, and a spring-pressed clutch pin carried by said housing engageable in a selected clutch groove for holding a selected sun gear in mesh with a selected group of pinions.

3. In a pipe threading machine, work supporting and rotating means comprising a table and supporting legs, a housing dependingly secured to said table, a chuck barrel journaled through said housing, said barrel being also shiftable endwise relative to said housing, a chuck fixed to one end of said barrel, a pair of sun gears fixed on said barrel in spaced apart relation, a bell gear journaled about said barrel, a ring gear fixed in said housing, low speed pinions rotatably carried by said bell gear, high speed pinions rotatably carried by said bell gear, all of said pinions meshing with said ring gear, means for rotating said bell gear, a bearing sleeve fixed to one of said pair of gears and formed with a pair of annular clutch grooves, a spring-pressed clutch pin carried by said housing engageable in a selected clutch groove for holding a selected sun gear in mesh with a selected group of pinions, and a clutch pin operating lever pivotally connected to said pin and rockably carried by said housing.
4. In a pipe threading machine, work supporting and rotating means comprising a table and supporting legs, a housing dependingly secured to said table, a chuck barrel journaled through said housing, a chuck on said barrel, change speed means for rotating said barrel, a cylindrical pipe guiding collar removably engaging in one end of said barrel, and a supporting guide dependingly fixed to said table in spaced relation to said collar.
5. In a pipe threading machine, work supporting and rotating means comprising a table and supporting legs, a pipe chuck, means rotatably supporting said chuck beneath said table, means for rotating said chuck, a cylindrical pipe guide spaced from said second means and axially aligning with said chuck, and means dependingly supporting said guide beneath said table.
6. In a pipe threading machine, work supporting and rotating means comprising a table and supporting legs, a pipe chuck, means rotatably supporting said chuck beneath said table, means for rotating said chuck, a cylindrical pipe guide spaced from said second means and axially aligning with said chuck, means dependingly supporting said guide beneath said table, a collar rotatably engaging said guide and anti-friction bearing means for said collar.
7. In a pipe threading machine, work supporting and rotating means, comprising a housing, a tubular chuck barrel journaled through said housing, a chuck on one end of said barrel, a high speed sun gear fixed on said barrel, a low speed sun gear fixed on said barrel, a driving gear rotatable about said barrel, means holding said driving gear against endwise movements, a sleeve fixed to said low speed sun gear and formed with a pair of spaced apart clutch grooves, said barrel having selected endwise movement relative to said housing, clutch means engageable in a selected groove, low speed pinions rotatably carried by said driving gear and adapted to selectively mesh with said low speed sun gear, high speed pinions rotatably carried by said driving gear and adapted to selectively engage with said high speed sun gear, a stationary ring gear fixed in said housing and meshing with said low and high speed pinions, and a reduction gearing connected with said driving gear.
8. In a pipe threading machine, work supporting and rotating means comprising a housing, a tubular chuck barrel journaled through said

housing, a chuck on one end of said barrel, a high speed sun gear fixed on said barrel, a low speed sun gear fixed on said barrel, a driving gear rotatable about said barrel, means holding said driving gear against endwise movement, a sleeve fixed to said low speed sun gear and formed with a pair of spaced apart clutch grooves, said barrel having selected endwise movement relative to said housing, clutch means engageable in a selected groove, low speed pinions rotatably carried by said driving gear and adapted to selectively mesh with said low speed sun gear, high speed pinions rotatably carried by said driving gear and adapted to selectively engage with said high speed sun gear, a stationary ring gear fixed in said housing and meshing with said low and high speed pinions, a reduction gearing connected

with said driving gear, and a flanged collar removably engaging in the end of said barrel opposite from said chuck.

9. In a pipe threading machine, work supporting and rotating means comprising a table and the supporting legs, a housing dependently secured to said table, a chuck barrel journaled through said housing, a chuck on said barrel, change speed means for rotating said barrel, a pipe guiding collar removably engaging in one end of said barrel, a cylindrical supporting guide dependently fixed to said table in alignment with and spaced from said collar, a pair of elongated stop members disposed one at each side of said table and means fixed relative to said table slidably supporting said stop members.

GILBERT J. SELLMEYER.
